ABSTRACT OF THE DISCLOSURE

1-(alkyleneiminocarbonyl)-N-(substituted carbamoyloxy)thioformimidates such as methyl 1-(pyrrolidinocarbonyl)-N-(methylcarbamoyloxy)thioformimidate which are useful in preventing the destructive effects of pests such as insects, ticks, mites and nematodes.

CROSS-REFERENCE TO RELATED APPLICATIONS

This application is a division of application Ser. No. 851,531, filed July 9, 1969, now U.S. Pat. 3,658,870, which is in turn a division of application Ser. No. 728,739, filed May 13, 1968, now U.S. Pat. 3,530,220, which is in turn a continuation-in-part of application Ser. No. 647,234, filed June 19, 1967, now abandoned.

SUMMARY OF THE INVENTION

This invention is a class of compounds of the formula:

wherein:

R₁ is alkyl of 1 through 4 carbon atoms or alkenyl of 3 through 4 carbon atoms;
R₄ is alkyl of 1 through 3 carbon atoms, allyl or propargyl;
R₅ is hydrogen or methyl; and
R₂ and R₃ are joined and are alkylene of 2 through 6 carbon atoms.

The background of this invention, and the manner and process of making and using it, are described in U.S. Pat. 3,530,220, the disclosure of which is incorporated by reference. Some representative compounds of this invention are listed below:

Methyl 1-(aziridinocarbonyl)-N-(methylcarbamoyloxy)thioformimidate
Methyl 1-(hexahydroazepinocarbonyl)-N-(methylcarbamoyloxy)thioformimidate
Methyl 1-(pyrrolidinocarbonyl)-N-(methylcarbamoyloxy)thioformimidate
Ethyl 1-(piperidinocarbonyl)-N-(allylcarbamoyloxy)thioformimidate

2

Ethyl 1-(piperidinocarbonyl)-N-(butylcarbamoyloxy)thioformimidate

Butyl 1-(piperidinocarbonyl)-N-(methylcarbamoyloxy)thioformimidate

5 Butyl 1-(piperidinocarbonyl)-N-(butylcarbamoyloxy)thioformimidate
Methyl 1-piperidinocarbonyl-N-(dimethylcarbamoyloxy)thioformimidate

The above named compounds are disclosed in Tables II and III which appear in columns 11 through 14 of U.S. Pat. 3,530,220.

I claim:

1. A compound of the formula:

wherein:

- 20 R₁ is alkyl of 1 through 4 carbon atoms or alkenyl of 3 through 4 carbon atoms;
R₄ is alkyl of 1 through 3 carbon atoms, allyl or propargyl;
R₅ is hydrogen or methyl; and
R₂ and R₃ are joined and are alkylene of 2 through 6 carbon atoms.
- 25 2. The compound of claim 1 which is methyl 1-(aziridinocarbonyl)-N-(methylcarbamoyloxy)thioformimidate.
- 30 3. The compound of claim 1 which is methyl 1-(hexahydroazepinocarbonyl)-N-(methylcarbamoyloxy)thioformimidate.
- 35 4. The compound of claim 1 which is methyl 1-(pyrrolidinocarbonyl)-N-(methylcarbamoyloxy)thioformimidate.
5. The compound of claim 1 which is ethyl 1-(piperidinocarbonyl)-N-(allylcarbamoyloxy)thioformimidate.
- 40 6. The compound of claim 1 which is ethyl 1-(piperidinocarbonyl)-N-(butylcarbamoyloxy)thioformimidate.
7. The compound of claim 1 which is butyl 1-(piperidinocarbonyl)-N-(methylcarbamoyloxy)thioformimidate.
- 45 8. The compound of claim 1 which is butyl 1-(piperidinocarbonyl)-N-(butylcarbamoyloxy)thioformimidate.
9. The compound of claim 1 which is methyl 1-piperidinocarbonyl-N-(dimethylcarbamoyloxy)thioformimidate.
